CENTRALIZED TRAFFIC CONTROL SYSTEM

Robert M. Phinney, Rochester, N. Y., assignor to
General Railway Signal Company, Rochester,
N. Y.

Application April 14, 1930, Serial No. 444,146

31 Claims. (Cl. 246—3)

This invention relates to centralized traffic controlling systems, and more particularly to such a system of the synchronous selector type employing cycles of impulses having distinctive starting characteristics.

Generally speaking the present invention is an improvement of the general system shown in the prior joint application of R. C. Leake and R. M. Phinney, Ser. No. 385,740, filed August 14, 1929, and contemplates the use of interconnecting circuits which make the system more positive in its operation, more economical and more reliable.

In the system of the prior application, each cycle of operation, insofar as the stepping operation is concerned, is exactly the same; for this reason a stepping relay is actuated at every way station in response to the first impulse of the stepping cycle. Obviously, it would be desirable to have some of the wayside locations unresponsive to certain cycles, whereas other wayside locations would respond to such cycles, so that a more economical system would result in that none of the wayside locations would require apparatus which would respond to each step in each cycle. Putting it in other words, it is proposed in accordance with the present invention to employ a synchronous selector system in which means is provided for distinctively starting the way station selectors, depending upon whether the first stepping impulse is of positive polarity or is of negative polarity. Generally speaking, the system, in accordance with the present invention is preferably divided in two parts, the selectors of one part of which start only if the first impulse in the stepping cycle is one of positive polarity, and the selectors of the other part of which start only if the first impulse is one of negative polarity, whereby the total impulses of a particular cycle can be approximately half the total number of message circuits of the entire system.

Another feature of the present invention consists in the provision of means for normally holding the system at rest, and consists in means for initiating a cycle of stepping impulses in which the first impulse is of positive polarity in the event that a lever is operated which requires a cycle of operation the first impulse of which is of positive polarity to transmit the desired control, and in providing means for initiating the system with a starting impulse of negative polarity in response to a lever movement, providing the lever moved is one of which transmits its control only during a cycle of impulses the first of which is of negative polarity; and in the provision of means for operating the system through both of these cycles in

the event there is a way station which is in condition for transmission of a change in traffic conditions, such as track occupancy.

Other objects, purposes and characteristic features of the present invention will in part be understood from the accompanying drawings and will in part be pointed out in the description hereinafter.

In describing the invention in detail, reference will be made to the accompanying drawings in which:

Figs. 1A and 1B, if laid end to end constitute a conventional showing of the devices and circuits in the central operator's office of the centralized traffic controlling system; and,

Fig. 2 conventionally shows two way stations of one form of way station apparatus adapted to be controlled by, and transmit indications to, the central office equipment shown in Figs. 1A and 1B.

The present invention contemplates operating the switch machines and signals at a large number of passing sidings on single track railroads, on double track railroads, at small interlocking plants, and in fact at any location where train movement must be dictated from a central office, such for instance as the junction point of a branch road with the main line. In other words, in accordance with the present invention there will be many wayside locations, even though the particular portion of the invention illustrated in the drawings shows only two such wayside locations, one at the west end of a passing siding PS and the other at the east end of such passing siding. It is contemplated that in the central office the entire railway system, to which the present invention is applied, is reproduced in miniature, as conventionally shown by the miniature passing siding ps (see Fig. 1A).

The passing siding PS (see Fig. 2) has the two track switches associated therewith, controlled by switch machines SM¹ and SM². The east end track switch is provided with the usual detector track circuit insulated from the rest of the system by insulating joints 16, and includes the usual track battery 17 and the usual detector track relay TR²; the west end of the passing sidings includes a similar track circuit, including a track battery 18 and a track relay TR¹. The east end of the passing siding PS is provided with the usual main starting signal EM, dwarf starting signal E^d, main entering signal WM and dwarf entering, or take-siding, signal W^d. These switch machines SM¹ and SM², and the signals associated with the track switches controlled by these switch machines, are controlled over the selector system embodying the

present invention, and of which only one specific embodiment has for convenience been illustrated.

Referring to Fig. 2 it will be noted that the series of stepping relays **1¹**, **2¹**, **3¹**, **4¹** and **5¹** are controlled by the line relay **LR¹** and the slow acting relay **I¹**; whereas the stepping relays **11²**, **12²**, **13²**, **14²** and **15²** are controlled by the line relay **LR²** and the slow acting relay **I²**. It is contemplated that the polar magnetic stick type relays **SR¹** and **DR¹**, which are used for controlling the signals at the west end of the passing siding **PS**, and the switch machine polar magnetic stick type relay **SMR¹** which controls the switch machine **SM¹**, will be controlled over the message line **20** through the medium of the stepping relays of that way-side location, namely, way station No. 1. Similarly the corresponding relays **SR²**, **DR²** and **SMR²** are controlled over the same message wire **20** through the medium of the stepping relays at the local office at the east end of the passing siding **PS**, namely, way station No. 2.

Attention is directed to the fact that the wiring of the various relays associated with way station No. 1 is exactly the same as the wiring of the various relays of way station No. 2, except in one particular, namely, that the main control contact **21** of the line relay **LR¹** has its left hand stationary contact **25** connected to the positive terminal of the battery **31** and has its right hand stationary contact **26** connected to the negative terminal of this battery **31**, whereas the stationary contacts of the corresponding movable contact **23** of the line relay **LR²** has its stationary contacts connected to the opposite terminals of the corresponding battery **32**.

Attention is now directed to the fact that in case the line relays **LR¹** and **LR²** are operated toward the right on the first step, as is the case when the line circuit **30** is energized with positive polarity, the slow acting relays **I¹** and **I²** will be picked up after a short time. Also, attention is directed to the fact that with the line relays **LR¹** and **LR²** operated toward the right, the stepping relay **1¹** will be picked up and the stepping relay **11²** will not be picked up, this because both sides of the coil of the stepping relay **11²** are connected to the same side, namely the positive terminal of the battery **32**. If, on the other hand, the line relays **LR¹** and **LR²** are operated toward the left during the first step, and before the slow acting relays **I¹** and **I²** have picked up, the stepping relay **11²** will pick up and the stepping relay **1¹** will not pick up. In other words, the stepping relays of way station No. 1 are operated only in the event that the operating cycle is started with a positive polarity impulse, and the stepping relays of way station No. 2 will only be operated in the event that the operating cycle is started with a negative impulse.

Let us now refer to Figs. 1A and 1B and observe the central office apparatus required to create the two different kinds of cycles of impulses, and the manner in which this office equipment cooperates with the way-side apparatus. The relays **LR^a**, **W^a**, **CR^a**, **E¹**, **E²**, **E³**, **I^a**, **A^a**, **B^a**, **1**, **2**, **3**, **4** and **5** shown in Fig. 1A correspond respectively to the relays **LR^b**, **W^b**, **CR^b**, **F¹**, **F²**, **F³**, **I^b**, **A^b**, **B^b**, **11**, **12**, **13**, **14** and **15** shown in Fig. 1B. These two groups of relays may be said to be the relays which enter into the stepping organization of the central office equipment.

The transfer relay **TR** is a relay that selects whether the stepping apparatus shown in Fig. 1A or the stepping apparatus shown in Fig. 1B shall be operated, and in this connection it may be

stated, that the stepping apparatus shown in Fig. 1A applies a starting impulse of positive polarity, whereas the stepping apparatus shown in Fig. 1B starts its cycle of impulses by an impulse of negative polarity. It may also be stated here, that the relay **FA** (see Fig. 1A) is a field starting relay, and is provided to initiate first the apparatus shown in Fig. 1A and then the apparatus shown in Fig. 1B, or vice versa, in the event a change of indication is to be transmitted from a wayside local office.

Also, it may be pointed out that the lever **LS¹** controls the signals at the west end of the passing siding **PS**, the lever **LSM¹** controls the switch machine **SM¹**, the lever **LS²**, controls the signals **EM**, **E^d**, **WM** and **W^d**, and the lever **LSM²** controls the switch machine **SM²**. Similarly, the indicating relays **IR¹** and **IR²** are controlled through the medium of the selector system in accordance with the condition of occupancy of the detector track circuits including track relays **TR¹** and **TR²** respectively.

The relays **A^a**, **B^a**, **A^b** and **B^b** may for convenience be called repeat-cycle relays, in that they cause the apparatus to go through two successive cycles in response to each initiation of the portion of the system in which they are contained.

The relays **E¹**, **E²**, **E³**, **F¹**, **F²** and **F³** may conveniently be called master relays, in that these relays are the ones that supply stepping current to the stepping wire **30**. Three of these relays are used, even though one would suffice, three being used in order to slow down the stepping operation of the system, and in this case it should be noted that the relay **E²** repeats the relay **E¹**, and the relay **E³** repeats the relay **E²**, as is also true of the relays **F¹**, **F²** and **F³**.

The relays **W^a** and **W^b** may conveniently be called control relays, because they must be energized in order to connect the stepping line to the central office equipment, or in other words they determine whether stepping impulses shall be transmitted to the way station apparatus.

The relays **CR^a** and **CR^b** may conveniently be called starting relays, in that these relays again pick up respectively the relays **W^a** and **W^b** after the completion of a cycle of operation followed by the necessary period of blank, which period of blank is determined by the time required for the slow acting relays **I^a** and **I^b** to again assume their deenergized position.

The relays **LR^a** and **LR^b** are of course the line relays, and the relays **1**, **2**, **3**, **4**, **5** and **11**, **12**, **13**, **14** and **15** are the stepping relays, or channel completing relays, a separate message channel extending from the central office equipment to a channel relay or channel contact at a distant way station, such a message channel being completed for each step in a cycle of operation of the system.

Having now briefly pointed out the purpose for which each relay of the system is used, it is considered expedient to consider the operation of the system in order to get a more clear understanding of the operating characteristics of the system and the economy experienced in dividing the various way stations into two groups, one group of which is operated only in the event a cycle is started with an impulse of positive polarity and the other group of which is only operated in the event the cycle is started with an impulse of negative polarity, each of these groups including a large number of way stations.

Operation.—Let us assume that the selector

system is in its normal at-rest condition and that the central office operator anticipates the approach of an east bound train which is to take the side track of the passing siding PS, and that he wishes to operate the switch machine SM¹ to the take-siding position. The operator will first move the switch machine lever LSM¹ from its right hand normal position to its left hand dotted position, thereby momentarily closing a pick-up circuit for the relays A^a and B^a readily traced in the drawings and including the wires 33 and 34. With this circuit momentarily completed the relays A^a and B^a will pick up, and the relay A^a will have its stick circuit, including its stick contact 35 and the back contacts 36 and 37 of the relays I^a and CR^a in multiple closed, so that the relay A^a will remain energized by current flowing in this stick circuit after the momentary closure of the pick-up circuit no longer maintains this relay energized. Similarly, a stick circuit is closed for the relay B^a, which includes its stick contact 38 and the back contact 39 of the channel selecting relay 4. In this connection it should be noted that the stick circuit for the relay B^a also includes the upper winding of the relay A^a, so that the relay A^a will not drop even though its stick circuit including its stick contact 35 is temporarily opened.

With the relay A^a picked up and its contacts 35, 41, 42 and 43 closed, the closure of the contact 43 completes an energizing circuit for the transfer relay TR. This circuit may be traced as follows:—beginning at the terminal B¹ of a suitable source of direct current, back contact 44 of the relay A^b (see Fig. 1B), wire 45, front contact 43 of the relay A^a, wires 46 and 47, upper winding of the transfer relay TR, to the other terminal B— of said source of current.

The completion of this circuit operates the transfer relay TR toward the left, thereby breaking the line circuit 30 insofar as the apparatus of Fig. 1B is concerned at the contact 48 of the relay TR, this contact 48 in its left hand position connecting the stepping wire 30 to the branch stepping line 30^a connected to the apparatus shown in Fig. 1A. Also, operation of the contact 49 of the transfer relay TR to its left hand position completes the following circuit for the starting relay CR^a:—beginning at the terminal B—, contact 49 of the transfer relay TR in its left hand position, wire 50, front contact 41 of the relay A^a, wire 51, winding of the starting relay CR^a, wire 52, back contact 53 of the relay I^a, to the other terminal B+ of said source. The completion of the circuit just traced picks up the starting relay CR^a, which relay CR^a then closes a pick-up circuit for the control relay W^a including the front contact 37 of the relay CR^a and readily traced in the drawings. With the relay W^a assuming its energized position the stepping line 30^a—30 is closed at the front contact 55 of the relay W^a, but this stepping circuit is still open at the contacts 54 and 85 of master relays E² and E³.

Also, picking up of the relay W^a applies current to the upper winding of the master relay E¹ operating this relay E¹ to a right hand position, which circuit may be traced as follows:—starting at the terminal B+, front contact 56 of the relay W^a, wire 57, back contact 58 of the stepping relay 1, wire 59, back contact 60 of the stepping relay 2, wire 61, back contact 62 of the stepping relay 3, wires 63, 64 and 65, upper winding of the relay E¹ to the terminal B—. The completion of this circuit causes the relay E¹ to be operated toward

the right, thereby causing its contacts 66 to apply current to the upper winding of the relay E² which current then operates the relay E² to the right and causes its contact 67 to apply current to the upper winding of the relay E³, thereby operating this relay to the right. With the relays E¹, E² and E³ assuming the right hand position, the stepping line 30 is energized by current of positive polarity through a circuit which may be traced as follows:—beginning at the terminal B+ of the central office battery, contact 54 of the relay E², toward the right, wire 66, contact 85 of the relays E³ to the right, wire 68, front contact 55 of the relay W^a, wire 69, line relay LR^a, wire 39^a, contact 48 of the transfer relay TR (see Fig. 1B), wire 30, line relay LR¹ (see Fig. 2), line wire 30, line relay LR², line wire 30 connected to the common return wire C at the distant end of the system, which common return wire C, may be grounded if desired, and is connected to the mid-point of the central office battery or other suitable direct current source.

The flow of current in the circuit just traced causes all of the line relays LR^a, LR¹, LR², etc. to be operated toward the right. Movement of the contact 70 of the line relay LR^a toward the right completes an energizing circuit for the stepping relay 1 as follows:—beginning at the terminal B+, contact 70 of the relay LR^a to the right, wire 71, back contact 72 of relay I^a, wire 73, bottom winding of the stepping relay 1, wires 74 and 75, back contact 76 of the stepping relay 2, wires 77 and 78, to the other terminal B—. The completion of this circuit picks up relay 1, which then sticks up as soon as the relay I^a reaches its energized position. This stick circuit may be traced as follows:—beginning at the terminal B+, front contact 53 of the relay I^a, wires 80 and 81, stick contact 82 of the relay 1, wire 83, upper winding of the relay 1, wires 84 and 75, back contact 76 of the relay 2, wires 77 and 78 to the other terminal B—.

Similarly, movement of contact 21 of the relay LR¹ toward the right, closes the following pick-up circuit for relay I¹:—beginning at the negative terminal of the battery 31, wires 27 and 26, contact 21 of relay LR¹, wire 102, back contact 103 of the relay I¹, wire 194, lower winding of relay I¹, wires 105 and 106, back contact 107 of the relay 2¹, wires 108 and 109, to the positive terminal of the battery. The relay I¹ when once picked up will of course stick up through the following stick circuit after relay I¹ has picked up:—beginning at the negative terminal of the battery 31, wires 112 and 113, front contact 114 of relay I¹, wires 115 and 116, stick contact 117, wire 118, resistance 119, upper coil of relay I¹, wires 120 and 106, back contact 107 of relay 2¹, wires 108 and 109, back to the battery 31.

With the relay I¹ picked up the main circuit for the upper winding of the relay E¹ is broken at the back contact 58 of the relay I¹, and an auxiliary energizing circuit for the upper winding of the master relay E¹ is completed which auxiliary energizing circuit may be traced as follows:—beginning at the terminal B+, front contact 56 of the relay W^a, wire 57, front contact 58 of the stepping relay 1, wire 81, front contact 88 of the relay CR^a, wires 89 and 65, upper winding of the relay E¹, to the other terminal B—.

Picking up of the slow acting relay I^a breaks the energizing circuit for the starting relay CR^a at the back contact 53 of the relay I^a, thus dropping the control relay CR^a and causing its contact 83 to shift the circuit for energizing the re-

lay E^1 from the upper winding to the lower winding of the master relay E^1 , and this shifting of the auxiliary circuit from the upper to the lower winding, these windings having their turns oppositely arranged, causes the master relay E^1 to be operated toward the left. Also, picking up of the slow acting relay I^a completes the following stick circuit for the relay W^a —beginning at the terminal $B+$, front contact 36 of the relay I^a , wire 90, back contact 91 of the stepping relay 5, wire 92, front stick contact 93 of the relay W^a , wires 94 and 95, winding of the relay W^a to the other terminal B , so that this relay W^a is stuck up and remains stuck up until either energization of the relay 5 has taken place or deenergization of the relay I^a has taken place.

The application of stepping current of positive and then of negative polarity alternately to the stepping wire 30 will of course operate the line relays LR^1 and LR^2 . It has been heretofore pointed out that dropping of the relay CR^a has shifted the circuit from the upper to the lower coil of the master relay E^1 and has caused this relay E^1 to be operated to the left. This in turn causes the relays E^2 and E^3 to be operated toward the left, thereby completing the following circuit for energizing the stepping line 30 with negative polarity—beginning at the terminal $B-$, contact 98 of the relay E^2 , wire 99, contact 85 of the relay E^3 toward the left, wire 68, front contact 55 of the relay W^a , wire 69, line relay LR^a , wire 30^a, contact 48 of the transfer relay TR , to the stepping wire 30 and through relays LR^1 and LR^2 to the distant end, which is connected to the common return wire C , which common return wire C is in turn connected to the mid-point of a suitable three terminal battery or generator (conventionally represented by the reference characters $B+$, $B-$ and C) in the central office. Operation of the line relay LR^a toward the left will close the pick-up circuit for the bottom winding of the stepping relay 2 through a circuit readily traced in the drawings and including a front contact 100 of the relay 1 and back contact 123 of the relay 3.

Similarly at way station No. 1, operation of the line relay LR^1 (see Fig. 2) to the left, picks up the relay 2¹ through a circuit readily traced and including front contact 124 of the relay 1¹ and back contact 125 of the relay 3¹. Picking up of the relays 2 and 2¹, will of course drop the relays 1 and 1¹ by reason of lifting of the contacts 76 and 107, respectively. Dropping of the contact 58 of the relay 1 (see Fig. 1A), removes energy from the wire 87, so that neither of the two auxiliary circuits for the relay E^1 can hereafter be completed; also, dropping of this contact 58 applies current to the upper winding of the relay E^1 through the following circuit—beginning at the terminal $B+$, front contact 56 of the relay W^a , wire 57, back contact 58 of the relay 1, wire 59, front contact 60 of the relay 2, wires 79, 64 and 65, upper winding of the relay E^1 to the terminal $B-$. The flow of current in this circuit will operate the relay E^1 to the right, which for reasons heretofore given causes the relays E^2 and E^3 to be sequentially moved to the right, thereby again applying stepping current of positive polarity to the stepping circuit 30, and affecting operation of the relays LR^a , LR^1 and LR^2 to the right.

With these line relays operated to the right hand position the stepping relay 3 is picked up through a circuit readily traced in the drawings, and including a front contact 133 of the

relay 2 and the back contact 134 of the relay 4, and similarly the relay 3¹ (see Fig. 2) is picked up through the medium of the front contact 135 of the relay 2¹ and the back contact 136 of the relay 4¹. These relays 3 and 3¹ having once been picked up will be stuck up through circuits readily traced in the drawings.

Attention is directed to the fact that when the slow acting relays I^a and I^1 were picked up the lifting of the contacts 130 and 131 of these relays disconnected the message wire 20 from the starting circuit branches, which will be described hereinafter, to the message branches of the two stepping relay groups 1-5, and 1¹-5¹. It will be remembered that the operator moved the lever LSM^1 toward the left and thereby initiated operation of the system by picking up the relays A^a and B^a through the medium of wires 33 and 34. With the relays 3 and 3¹ now picked up and stuck up, even though these relays only remain in their energized stuck-up position for a moment, the following message circuit is completed for a sufficient period of time to operate the switch machine relay SMR^1 to its left hand position—beginning at the terminal $B-$, contact 138 of the lever LSM^1 , wire 139, front contact 140 of the stepping relay 3, wire 141, back contact 142 of the relay 2, wire 143, back contact 144 of the relay 1, wire 145, contact 146 of relay E^3 , to the right, wire 147, contact 148 of the relay E^2 to the left, (this message circuit being completed when the relays E^1 and E^2 have already been moved to the left but the relay E^3 has not yet been moved to the left during the fourth step of these relays), wire 149, front contact 150 of the relay I^a , message wire 20, wire 150, (see Fig. 2) front contact 151 of the relay I^1 , wire 151, back contact 152 of the relay 1¹, wire 153, back contact 154 of the relay 2¹, wire 155, front contact 156 of the relay 3¹, wire 157, winding of the switch machine relay SMR^1 , wire 158, front contact 159 of the relay 3¹, wire 160, back contact 161 of the relay 4¹, wire 162, back contact 163 of the relay 5¹, wire 164 of the common return wire C connected to the mid-point of the central office battery.

The flow of current of negative polarity through this relay SMR^1 operates this relay to its left hand dotted position, and since this relay SMR^1 is of the magnetic stick type, it will remain in the left hand position after having been operated there in response to the momentary flow of current of negative polarity. Attention is directed to the fact that the message circuit at way station No. 1, just traced, includes back contacts of the relays 1¹, 2¹, 4¹ and 5¹ and includes front contacts of the relay 3¹. The purpose of this feature is to check the positions of the various relays, so that the unauthorized sticking up of a channel or stepping relay will prevent the closure of any message circuit. In this connection it should be noted that the stepping relay 5¹ is not used as a channel selecting relay, it having no channel through a front contact, but is merely used to check against a false sticking up of the relay 4². In other words, if one of the relays should remain up, for any reason, the picking up of a second relay would not permit any message channel circuit to be completed. Putting it another way, the channel circuit branches are so interlocked that no channel circuit can be completed when two of these relays are in their energized positions.

After a short interval of time the relay E^3 will also be operated to the left hand position 75

in response to movement of the relays E^1 and E^2 toward the left, the relay E^1 having been moved toward the left in response to the application of current of positive polarity to the wire 166. Operation of the relay E^3 to the left applies current of negative polarity to the stepping wire 30, thereby operating the relay LR^a and LR^1 toward the left and closing pick-up circuits for the relays 4 and 4 ^{1} , which include the front contact 167 of relay 3 and back contact 168 of relay 5, and the front contact 169 of relay 3 ^{1} and back contact 170 of relay 5 ^{1} , respectively. These relays 4 and 4 ^{1} will then be stuck up through stick circuits readily traced in the drawings, and will effect deenergization of the relays 3 and 3 ^{1} .

Dropping of the relay 3 will again apply current of positive polarity to the wire 64 leading to the upper coil of the relay E^1 , thereby operating the relay E^1 toward the right, and this relay E^1 in turn will effect operation of the relays E^2 and E^3 toward the right. Movement of the relay E^3 toward the right causes current of positive polarity to be applied to the stepping wire 30, thus operating the line relays LR^a and LR^1 toward the right, and thereby picking up the relays 5 and 5 ^{1} through pick-up circuits including the front contact 172 of relay 4 and 173 of relay 4 ^{1} , respectively. The relays 5 and 5 ^{1} will then be stuck up through stick circuits readily traced in the drawings, and for obvious reasons their picking up will effect deenergization of the relays 4 and 4 ^{1} .

Picking up of the relay 4 heretofore opened the stick circuit including the relay B^a and the upper coil of the relay A^a , thereby effecting deenergization of the relay B^a , but the relay A^a remained stuck up through its stick circuit including its contact 35 and the back contact 37 of the relay CR^a . Also, picking up of the relay 5 as has just happened, will open its back contact 91 and thereby break the stick circuit for the relay W^a to effect deenergization of this relay W^a .

With the relay W^a deenergized the line circuit 30 is deenergized, thereby causing the line relays LR^a , LR^1 and LR^2 to assume their deenergized pendent positions, and with the contacts 28 and 22 of the relays LR^a and LR^1 assuming their pendent position the relays I^a and I^1 will assume their deenergized positions. Dropping of the relay I^1 will effect dropping of the relay 5 ^{1} by reason of opening of contact 114 of relay I^1 . Dropping of the relay I^a will, through the medium of its front contact 53 drop the relay 5, and through the medium of its back contact 53 again picks up the starting relay CR^a , the contact 41 of the relay A^a still being closed, and the transfer relay TR still assuming its left hand dotted position.

Picking up of the relay CR^a again closes the pick-up circuit for the relay W^a through its contact 37, and this relay W^a will then again apply current of positive polarity to the stepping line 30, thereby causing the relays I^a and I^1 again to be picked up in response to movement of line relays LR^a and LR^1 toward the right, and also effecting picking up of the slow acting relays I^a and I^1 . Picking up of the relay I^a will of course again close the stick circuit for the relay W^a at the front contact 36 of the relay I^a . The entire cycles of operation of the portion of the system shown in Fig. 1A and the way station No. 1 will then be repeated. In this connection it should be noted that during the time when the relay I^a has already been picked up and the relay CR^a

has not yet dropped in response to this picking up of the relay I^a the stick circuit for the relay A^a is open at the two back multiple contacts 36 and 37 of the relays I^a and CR^a , so that the relay A^a assumes its deenergized position and the system comes to a stop at the end of a second cycle, this because the starting relay CR^a has its energizing circuit broken at the contact 41 of the relay A^a at the time of dropping of relay I^a at the end of the second cycle, so that the relay CR^a remains down until the relay A^a is again picked up.

It has been pointed out how the switch machine relay SMR^1 is moved to the left hand dotted position, this movement of the relay SMR^1 to the left effects operation of the switch machine SM^1 to its take-siding position through suitable means conventionally shown by the dotted line 175, so that the east bound train may pass into the side track of the passing siding PS .

Let us now assume that the central office operator, after having allowed another train to move over the main track, wishes to allow the east bound train to continue its east bound movement, and therefore moves the switch machine lever LSM^2 to its left hand dotted position. This movement of the lever LSM^2 to its left hand position momentarily applies current to the repeat cycle relays A^b and B^b through the following circuit:—starting at the terminal B^+ , lever LSM^2 , wires 177, 178, 179, and 180, winding of the relay B^b , wire 181, upper winding of the relay A^b , to the terminal B^- . With the relays A^b and B^b picked up, the relay A^b will be stuck up through its stick contact 182, and the back contacts 183 of relay I^b and 184 of relay CR^b , in multiple, and the relay B^b will be stuck up through its stick contact 185 and the back contact 186 of the stepping relay 14.

With the relays A^b and B^b energized and the relay A^a deenergized, the lower winding of the transfer relay is energized through the following circuit:—beginning at the terminal B^+ , back contact 42 of the relay A^a , wire 190, front contact 191 of the relay A^b , wires 192 and 193, lower winding of the relay TR , to the terminal B^- . The completion of this circuit operates the transfer relay TR back to its normal position, thereby connecting the stepping wire 38 b to the stepping line 30. Movement of the transfer relay TR to its right hand position also closes the following circuit for the starting relay CR^b :—beginning at the terminal B^- , contact 49 of the transfer relay TR , wire 195, front contact 196 of the relay A^b , wire 197, winding of the starting relay CR^b , wire 198, back contact 199 of the relay I^b , back to terminal B^+ of the same source. Picking up of the starting relay CR^b closes the pick-up circuit for the control relay W^b through a circuit including the front contact 184 of relay CR^b and the wires 200 and 201.

Picking up of the relay W^b applies current to the lower winding of the master relay F^1 , through the following circuit:—beginning at the terminal B^+ , front contact 203 of the relay W^b , wire 204, back contact 205 of the relay I^2 , wire 206, back contact 207 of the relay I^2 , wire 208, back contact 209 of the relay I^3 , wires 210, 211, and 212, lower winding of relay F^1 . The application of current to the lower winding F^1 moves this relay F^1 to its left hand position thereby sequentially operating the relays F^2 and F^3 to their left hand dotted position, and movement of the relay F^3 to its left hand position applies current of negative polarity to the stepping wire 30 through the fol-

lowing branch circuit:—beginning at the terminal B—, contact 214 of the relay F² toward the left, wire 215, contact 216 of the relay F³ to the left, wire 217, front contact 218 of the relay W^b, wire 219, winding of the relay LR^b, wire 30^b, contact 48 of the transfer relay TR to the right, stepping line 30, line relay LR¹ (see Fig. 2), wire 30, line relay LR², wire 30, through the rest of the line relays, to the common return wire C, connected to the mid-point of the central office battery. It is of course noted that during this energization of the stepping line 30, the line relay LR^a is not included in the circuit whereas heretofore the line relay LR^b was not included in this circuit, so that the line relays LR^b, LR¹, LR² will now be simultaneously operated to their left hand position.

Operation of the line relay LR² to its left hand position closes the following pick-up circuit for the relay 11²:—beginning at the negative terminal of the battery 32, wires 220, 221 and 222, contact 223 of the relay LR² to the left, wire 223, back contact 224 of the relay I², wire 225, lower winding of the relay 11², wires 226 and 227, back contact 228 of the relay 12², wires 229 and 230, back to the battery 32. The completion of the circuit just traced picks up the relay 11², which then in response to picking up of the relay I² is stuck up through the following stick circuit:—beginning at the negative terminal of the battery 32, wires 220 and 232, from contact 233 of the relay I², wires 234 and 235, front stick contact 236 of the relay 11², resistance unit 237, upper winding of the relay 11², wires 238 and 227, back contact 228 of the relay 12², wires 229 and 230, back to the battery 32.

It may be pointed out here, that the resistance unit 237, which is included in a stick circuit just traced, is used for the purpose of decreasing the current flowing in this stick circuit and consequently reduces the arcing at the contacts when the relay I² is again deenergized by breaking of this stick circuit. It is of course understood that after a relay is once picked up it will stick up on a much smaller current than is required to pick such relay up.

Referring now to way station No. 1 it will be noted that movement of the line relay LR¹ toward the left will after a short time effect energization of the slow acting relay I¹, but will not effect energization of the stepping relay 11, because the circuit closed through the lower winding of the relay 11 does not include a source of energy, both terminals of this lower winding of relay 11 terminating at the positive side of the battery 31.

With the apparatus shown in Fig. 1B once initiated it will run through two cycles of operation in the same manner as will the apparatus shown in Fig. 1A, and since the repeat features have been described in connection with the apparatus in Fig. 1A, it is deemed unnecessary to specifically describe all the steps of this operation and to trace all the various circuits involved. It may be pointed out that the principal difference between the stepping apparatus shown in Fig. 1A and the stepping apparatus shown in Fig. 1B is that initiation of the system shown in Fig. 1A causes the relays E¹, E² and E³ to be moved to the right in response to energization of the upper coil of relay E¹, whereas the initiation of the system shown in Fig. 1B causes the relays F¹, F² and F³ to be moved to the left in response to energization of the lower winding of relay F¹, in all other respects relays in Fig. 1A are wired exactly the same as are the corresponding relays in Fig. 1B.

Similarly, referring to Fig. 2, the relays I¹, I², 21, 31, 41 and 51 are wired up exactly the same as are the relays LR², I², 11², 12², 13², 14² and 15², respectively, except that the contact 21 of relay LR¹ when in its right hand position is connected to the negative terminal of the battery 31, whereas the corresponding contact 23 of the line relay LR² when assuming its right hand position is connected to the positive terminal of the battery 32, from which it is apparent that the bank of stepping relays shown at way station No. 1 will only operate if the first impulse of the cycle is of positive polarity, whereas the stepping relays at the way station No. 2 will only operate if the first step of the cycle of impulses is of negative polarity.

From the foregoing it is apparent that the stepping relay 13 and the stepping relay 13² will assume their attracted positions simultaneously and during the time when these two stepping relays 13 and 13² are up and their adjacent stepping relays are down, and while the relay F² assumes its right hand position and the relay F³ assumes its left hand position the following message circuit, for operating the switch machine for SMR², is closed:—beginning at the terminal B—, contact 240 of the lever LSM² assuming its left hand position, wire 241, front contact 242 of the relay 13, wire 243, back contact 244 of the relay 12, wire 245, back contact 246 of the relay 11, wire 247, contact 248 of the relay F³ toward the left, wire 249, contact 250 of the relay F² to the right, wire 251, front contact 252 of the relay 1^b, wire 253, message wire 20, wire 254 (see Fig. 2), front contact 255 of the relay I², wire 256, back contact 257 of the relay 11², wire 258, back contact 259 of the relay 12², wire 260, front contact 261 of the relay 13², wire 262, winding of the switch machine relay SMR², wire 263, front contact 264 of the relay 13², wire 265, back contact 266 of the relay 14², wire 267, back contact 268 of the relay 15², wire 269, to common return wire C connected to the mid-point of the central office battery.

Completion of the circuit just traced operates the switch machine relay SMR² to its left hand dotted position, thereby operating the switch machine SM² to its take-siding position, allowing the east bound train to move off of the siding as soon as the dwarf signal E^d is cleared.

This dwarf signal E^d may be cleared by operation of the signal relay SR² to its right hand position, the direction relay DR² already assuming its east bound position, and this relay SR² may be operated to its right hand position by movement of the signal lever LS² to its right hand position, whereby during the simultaneous energization of the stepping relays 11 and 11² causes a momentary flow of current to the signal relay SR², through a message circuit readily traced in the drawings. This flow of current operates this relay SR² to its right hand position, thereby clearing this dwarf starting signal E^d through a suitable circuit conventionally shown by the dotted line 270, all in a manner as clearly disclosed in the prior application of S. N. Wight, Ser. No. 321,185, filed November 22, 1928.

As the east bound train now proceeds into the single track section in response to clearing the dwarf starting signal E^d it will tread upon the detector track circuit and effect deenergization of the track relay TR². Dropping of the track relay TR² effects momentary energization of the relay QR² through the following circuit:—beginning at the terminal B+ and back contact 271

of the relay TR^2 , wire 272, front contact 273 of the relay PR^2 , wires 274 and 275, winding of the relay QR^2 to the other terminal B^- . It may be mentioned here that if the system is at this time in operation the relay QR^2 will be stuck up through a stick circuit including the stick contact 276 and the front contact 277 of the relay I^2 . Also, upon picking up of its detector track relay TR^2 , or any other relay the position of which is to be indicated in the central office, the relay QR^2 will be picked up through the back contact 273 of the relay PR^2 , the relay PR^2 being slower acting than the relay QR^2 . For a more complete description of the relays PR^2 and QR^2 attention is directed to the prior application of R. C. Leake and R. M. Phinney, above referred to.

Picking up of the relay QR^2 closes the following circuit for the field starting relay FA :—beginning at the positive terminal of the battery 280 (see Fig. 1A), winding of the field starting relay FA , wire 281, back contact 130 of the relay I^a , message wire 20, wire 254 (see Fig. 2), back contact 255 of the relay I^2 , wire 282, front contact 283 of relay QR^2 , to the common return wire C connected to the negative terminal of the battery 280. Momentary energization of the relay FA , causes it to close its contacts 284 and 285, thereby closing pick-up circuits for the relays A^a , B^a , A^b and B^b , readily traced in the drawings. With these four relays simultaneously energized the transfer relay TR will be left in the position it is then assuming, and if it is then assuming the left hand position it will initiate the apparatus shown in Fig. 1A, whereas if it assumes its right hand position it will initiate the apparatus shown in Fig. 1B, and in each case after the apparatus first selected has been operated through one cycle, all in a manner as heretofore described, the A relay of that apparatus will drop at the end of the second cycle. Before the A relay drops, and specifically when the last stepping relay of that group picks up, the transfer relay TR will be operated to its opposite position.

Let us now consider more specifically this operation of the transfer relay TR . Let us take up the operation where we left it, that is, with the relays A^a , B^a , A^b and B^b all energized and with the first cycle completed. Just before this cycle was completed, namely with the the stepping relay 5 up, completion of the following circuit operates the transfer relay TR to its right hand position:—beginning at the terminal B^+ , front contact 44 of the relay A^b , wire 127, front contact 126 of the stepping relay 5, wires 128 and 193, bottom coil of the relay TR , to the other terminal B^- . With the relay TR assuming its right hand position and the relay A^b assuming its attracted position, the apparatus shown in Fig. 1B is operated through one cycle of operation in a manner as already described. When, during this cycle of operation of the apparatus shown in Fig. 1B, the relay 15 assumes its energized position, the transfer relay TR is operated to its left hand position through the following circuit:—beginning at the terminal B^+ , front contact 42 of relay A^a , wire 137, front contact 138 of the stepping relay 15, wires 139 and 41. With the transfer relay now assuming its left hand position and the relay A^a still up, the apparatus shown in Fig. 1A is again operated through a cycle of operation, at the end of which the relay A^a is deenergized. With the relay A^a now deenergized and relay A^b still energized the transfer relay TR is again operated to its right

hand position in a manner presently described in detail.

Briefly stated, this transfer relay TR can only be operated in a manner presently described if one of the relays A^a or A^b is energized and the other is deenergized, from which it is apparent that if both of these relays A^a and A^b are simultaneously energized the transfer relay TR can only be operated through the medium of contacts 126 and 138 of relays 5 and 15, respectively, so that the transfer relay will, with both of the relays A^a and A^b energized select that half of the dispatcher's equipment previously selected by the transfer relay TR depending upon the position it then assumed, and that as soon as a cycle is completed or one of the relays A^a or A^b is deenergized the transfer relay TR will be operated to the opposite position.

I have now pointed out how the system may be initiated from the field and how such initiation from the field causes the apparatus in Fig. 1A to operate through one cycle of operation, the apparatus shown in Fig. 1B to operate through one cycle of operation, after which the apparatus of Fig. 1A again operates through one cycle followed by a cycle of operation of the apparatus shown in Fig. 1B, from which it is apparent that during such operation, the relays 14 and 14² will be simultaneously assuming their attracted positions and when this occurs the indicating relay IR^2 (see Fig. 1A) is operated by current of negative polarity through the following message circuit:—beginning at the negative terminal of the battery 290 (see Fig. 2), back contact 291 of the relay TR^2 , wire 292, front contact 293 of the relay 14², wire 294, back contact 261 of the relay 13², wire 260, back contact 259 of the relay 12², wire 258, back contact 257 of the relay 11², wire 256, front contact 255 of the slow acting relay I^2 , wire 254, message wire 20, wire 253, front contact 252 of the relay I^b , wire 251, contact 250 of the relay F^2 to the right, wire 249, contact 248 of the relay F^3 to the left, wire 247, back contact 246 of the relay 11, wire 245, back contact 244 of the relay 12, wire 243, back contact 242 of the relay 13, wire 296, front contact 297 of the relay 14, wire 298, winding of the relay IR^2 , to the common return wire C connected through wires 269 (see Fig. 2), back contact 268 of relay 15², wire 267, front contact 266 of relay 14² and wire 299 to the mid-point of the battery 290. The completion of this message circuit will of course operate the indicating relay IR^2 to the left and illuminate the lamp L^2 , manifesting to the operator that the train is leaving the passing siding at the east end. The relays QR^1 and PR^1 are provided for the same purpose and function in the same way as do the relays QR^2 and PR^2 .

Summary operation.—Considering the system at rest and with the relays all positioned as shown, and assuming that the system is initiated by moving either the lever LS^1 or the lever LSM^1 , the following relay operations will take place:—relays B^a and A^a pick up, stick circuits for relays B^a and A^a completed, top coil for transfer relay TR energized operating TR to left, relay CR^a energized, relay W^a energized, top coils of relays E^1 , E^2 and E^3 energized operating these relays to the right, line relays LR^a and LR^1 operated to the right, relays 1 and 1¹ picked up and stuck up and message circuit completed, top coil relay E^1 opened and auxiliary circuit for top coil of relay E^1 closed, relays I^a and I^1 picked up, stick circuit for relay W^a completed, relay CR^a dropped, 75

bottom circuit for relay E^1 closed and auxiliary circuit for top coil of relay E^1 opened, operates relays E^1 , E^2 , E^3 to the left, line relays LR^a and LR^1 operated toward the left, relays 2 and 2^1 picked up, relays 4 and 4^1 dropped, second message circuit completed, both auxiliary circuits for relay E^1 opened and main circuit for top coil of relay E^1 closed, line relays LR^a and LR^1 operated to the right, relays 3 and 3^1 picked up, relays 2 and 2^1 dropped and third message circuit completed, main circuit for upper coil of relays E^1 opened and main circuit for lower coil of relay E^1 closed, relays E^1 , E^2 and E^3 operate to left, line relays LR^a and LR^1 operate to left, relays 4 and 4^1 picked up, relay B^a dropped, relays 3 and 3^1 dropped and fourth message circuit completed, main circuit for bottom coil relay E^1 opened and main circuit for top coil of relay E^1 closed, relays E^1 , E^2 , E^3 , LR^a and LR^1 operate to right, relays 5 and 5^1 picked up, relays 4 and 4^1 dropped and fifth message circuit completed, relay W^a dropped opening the stepping circuit, relays LR^a and LR^1 deenergized, relays I^a and I^1 dropped, relay CR^a picked up, relay W^a picked up, after which the same cycle of operation is repeated. It may be pointed out here that the devices are not necessarily operated in the exact order above given in that some of these operations occur in multiple, so to speak, so that the exact order in which these operations take place depends somewhat on the operating characteristics of the relays involved. This summary of relay operations has for convenience been limited to the positive starting portion of the system, and has been given to aid a person in the study of the system disclosed in the drawings.

Although applicant has illustrated one rather specific embodiment of his invention, this is not to be construed as a limitation upon the scope of his invention, nor is the system shown to be construed as the exact construction preferably employed in practicing the invention, but should be considered as an exemplification of a system having certain desirable operating characteristics underlying the present invention; for instance, suitable interlocking neutral relays could be used instead of the polar relays E^1 , E^2 and E^3 , and other suitable control relays may be used instead of the relays SR^1 , DR^1 , SMR^1 , etc., and many other changes, modifications and additions may be made to adapt the invention to the particular problem encountered in practicing the same, without departing from the spirit or scope of the invention, except as demanded by the scope of the following claims.

What I claim as new is:—

1. In a remote control system of the synchronous selector type, the combination with two separate series of stepping relays in a central office and a series of stepping relays at each of a plurality of way stations, means whereby one of said two series of stepping relays operates to apply a series of stepping impulses to a stepping line connecting said office and way stations the first of which is positive, means whereby the other of said two series of stepping relays operates to apply a series of stepping impulses to said stepping line the first of which is of negative polarity, means whereby some of said way station series of stepping relays respond only when the first impulse of a series of impulses is positive, means whereby other series of way station relays respond only when the first impulse of a series is of negative polarity, and means for transmitting distinctive signals when certain and correspond-

ing stepping relays assume their energized position.

2. In a remote control system of the synchronous selector type, the combination with two separate series of stepping relays in a central office and a series of stepping relays at each of a plurality of way stations, means whereby one of said two series of stepping relays operates to apply a series of stepping impulses to a stepping line the first impulse of which is positive, means whereby the other of said two series of stepping relays operates to apply a series of stepping impulses to said stepping line the first of which is of negative polarity, means whereby some of said way station series of stepping relays respond only when the first impulse of a series of impulses is positive, means whereby other series of way station relays respond only when the first impulse of a series is of negative polarity, and means completing a plurality of message circuits sequentially each including the same line wire during a particular cycle of operation.

3. In a remote control system of the synchronous selector type, the combination with two separate series of stepping relays in a central office and a series of stepping relays at each of a plurality of way stations, means whereby one of said two series of stepping relays operates to apply a series of stepping impulses to a stepping line the first of which is positive, means whereby the other of said two series of stepping relays operates to apply a series of stepping impulses to said stepping line the first of which is of negative polarity, means whereby some of said way station series of stepping relays respond only when the first impulse is positive, means whereby other series of way station relays respond only when the first impulse of a series is of negative polarity, and means completing a plurality of message circuits sequentially each including the same line wire during each of the two distinctive cycles of operation obtainable by said two separate series of stepping relays.

4. In combination, a line circuit having two polar line relays therein, a series of stepping relays controlled by each of said line relays, a slow acting relay associated with each of said line relays each assuming its energized position if the associated line relay assumes either of its polar positions either intermittently or permanently, a first stepping relay of one of said series of stepping relays having an energizing circuit including a back contact of said associated slow acting relay and a contact closed if said associated line relay assumes its positive position, a first stepping relay of the other series of stepping relays having an energizing circuit including a back contact of said associated slow acting relay and a contact closed when its associated line relay assumes its negative position, whereby the first relay of one series of stepping relays is picked up only if the first impulse of a cycle is of positive polarity and the first relay of the other series is picked up only if the first impulse of a cycle is of negative polarity, and means responsive to the operation of each of said first stepping relays for selecting the next stepping relay of its series.

5. In combination, a line circuit having two polar line relays therein, a series of stepping relays associated with each of said line relays, a slow acting relay associated with each of said line relays each assuming its energized position if the associated line relay assumes either of its polar positions either intermittently or permanently, a first stepping relay of one of said se-

ries of stepping relays having an energizing circuit including a back contact of said associated slow acting relay and a contact closed if said associated line relay assumes its positive position, a first stepping relay of the other series of stepping relays having an energizing circuit including a back contact of said associated slow acting relay and a contact closed when its associated line relay assumes its negative position 5 whereby the first relay of one series of stepping relays is picked up only if the first impulse of a cycle is of positive polarity and the first relay of the other series is picked up only if the first impulse of a cycle is of negative polarity, 10 and means for transmitting distinctive signals as selected by additional stepping relays of a series in accordance with whether the first relay of one series or the first relay of the other series of stepping relays is energized.

20 6. In combination, a line circuit having two polar line relays therein, a series of stepping relays associated with each of said line relays, a slow acting relay associated with each of said line relays each assuming its energized position 25 if the associated line relay assumes either of its polar positions either intermittently or permanently, a first stepping relay of one of said series of stepping relays having an energizing circuit including a back contact of said associated slow acting relay and a contact closed if said associated line relay assumes its positive position, a first stepping relay of the other series of stepping relays having an energizing circuit including a back contact of said associated slow 30 acting relay and a contact closed when its associated line relay assumes its negative position whereby the first relay of one series of stepping relays is picked up only if the first impulse of a cycle impressed on said line circuit is of positive polarity and the first relay of the other series is picked up only if the first impulse of a cycle is of negative polarity, means for transmitting distinctive signals as selected by additional stepping relays of a series in accordance 35 with whether the first relay of one series or the first relay of the other series of stepping relays is energized, and a circuit for picking up the second relay of a series including a front contact of said slow acting relay and a front contact of the first relay of the same series.

50 7. In combination, one set of line wires, two sets of sending apparatus for transmitting distinctive signals over said one set of line wires, a two-position polar relay for effecting use of said set of line wires by one or the other of said sets of sending apparatus, an initiating relay for each set of sending apparatus, and means for operating said polar relay to one position when one of said initiating relays is energized and the other initiating relay is de-energized and for operating said polar relay to its opposite position when said other initiating relay is energized and said first initiating relay is deenergized.

55 8. In a synchronous selector centralized traffic controlling system of the message wire type comprising, a series of stepping relays, means for successively picking up said relays one at a time, a message wire and a common return wire, contacts on said stepping relays for successively completing distinct message circuits one at a time and one for each stepping relay and each including said message wire and said common wire, and each of said message circuits including a contact of each of said stepping relays which contacts are so associated with said relays

that in the event two relays are up at the same time no message circuit can be completed.

9. In a remote-control system of the synchronous selector type; a plurality of stations; a stepping circuit connecting said plurality of stations; means applying a series of impulses to said stepping circuit; means determining the character of the first impulse of said series of impulses; a series of stepping relays located at each station, certain of said series of stepping relays being responsive to said series of impulses only when the first impulse is of one character, and certain other of said series of stepping relays being responsive to said series of impulses only when the first impulse is of another character; and means for transmitting distinctive signals only when certain and corresponding relays respond to said series of impulses.

10. In a remote control system of the synchronous selector type; a plurality of stations; a stepping circuit connecting said plurality of stations; means applying a series of impulses to said stepping circuit; means determining the character of the first impulse of said series of impulses; a series of stepping relays located at each station, certain of said series of stepping relays being responsive to said series of impulses only when the first impulse is of one character, and certain other of said series of stepping relays being responsive to said series of impulses only when the first impulse is of another character; and means completing a plurality of message circuits, each of said message circuits being completed only when certain and corresponding stepping relays respond to corresponding impulses of said series of impulses.

11. In combination; one set of line wires; two sets of sending apparatus each being operable through cycles of operation for transmitting distinctive signals over said one set of line wires; a two-position polar relay for effecting use of said set of line wires during an operating cycle by one or the other of said two sets of sending apparatus; two initiating relays, one for each set of sending apparatus for starting its corresponding set of apparatus when said two-position polar relay is in a corresponding position and that initiating relay is energized; means for operating said polar relay to a position into correspondence with a particular initiating relay when that initiating relay is energized and the other initiating relay is deenergized; and means for operating said polar relay to alternate positions for successive cycles of operation when both of said initiating relays are energized.

12. In combination, a series of stepping relays, means for successively energizing and successively deenergizing said relays so that only one stepping relay can remain energized at any one time, a message wire, a common return wire, and contacts on each of said stepping relays for completing a plurality of message circuits between said message wire and said common wire, each of said message circuits including a front contact of the stepping relay energized for that step and a back contact of every other stepping relay of the series.

13. In a remote control system, a stepping line circuit, a plurality of polarized line relays included in said line circuit, a stepping relay bank associated with each of said line relays, means placing a plurality of series of distinctive impulses upon said line circuit, means determining the character of the first impulse of each series, and means causing only certain of said

plurality of stepping relay banks to respond to any particular one of said series of distinctive impulses depending upon the character of the first impulse of such series.

- 5 14. In a remote control system, a stepping line circuit, means placing a plurality of series of impulses on said stepping line circuit, means determining the character of the impulses of each series, a plurality of stepping relay banks, 10 a line relay for each stepping relay bank for responding to the impulses of any series, means causing certain of said plurality of stepping relay banks to be responsive to their respective line relays only when the first impulse of a series is of 15 one character, and means causing certain others of said plurality of stepping relay banks to be responsive to their respective line relays only when the first impulse of a series is of another character.
- 20 15. In combination, a line circuit having a plurality of polar line relays included therein, means for impressing a plurality of impulses of selected polarities on said line circuit, means responsive to said impulses for operating said 25 line relays, a neutral relay for each polar line relay, each of said neutral relays having an energizing circuit closed when its corresponding polar line relay assumes either of its polar positions, a stepping relay bank associated with each 30 of said polar line relays, a pick-up circuit for the first relay in each of certain of said stepping relay banks, said circuits being energized only during the pick-up period of said neutral relay when their corresponding polar relays assume 35 certain polar positions, a pick-up circuit for the first relay in each of certain other of said stepping relay banks, said circuits being energized only during the pick-up period of said neutral relays when their corresponding polar relays assume 40 certain other polar positions, and means responsive to the operation of said polar relays following the operation of said neutral relays and said first stepping relays for operating the other stepping relays in the associated banks.
- 45 16. In combination, a line circuit interconnecting a plurality of stations, a polar line relay included in said line circuit at each of said stations, means for impressing a plurality of impulses of selected polarities on said line circuit, 50 means responsive to said impulses for operating said line relays, a neutral relay at each station having an energizing circuit closed when its corresponding polar line relay assumes either of its polar positions, other relay means at each 55 station selectively controlled in accordance with the polar position of its corresponding polar line relay only during the pick-up period of its corresponding neutral relay, whereby said stations are selectively divided into groups in accordance with a polar impulse applied to said line circuit, and selector means responsive to the further 60 operation of the line relay only at a station selected by said polar impulse.
17. In combination, a line circuit interconnecting a control office and a plurality of stations, a polar line relay included in said line circuit at each of said stations, means for impressing a plurality of impulses of selected polarities on said line circuit, means responsive to said impulses for operating said line relays, a neutral relay at each station having an energizing circuit closed when its corresponding polar line relay assumes either of its polar positions, station selecting means at each station selectively controlled in 65 accordance with the polar position of its corre-

sponding polar line relay only during the pick-up period of its corresponding neutral relay, whereby said stations may be remotely selected over said line circuit, and selector means responsive to the operation of the line relay only at a selected station. 65

18. In combination, a line circuit interconnecting a plurality of stations, a polar line relay included in said line circuit at each of said stations, means for impressing a plurality of impulses of selected polarities on said line circuit, means responsive to said impulses for operating said line relays, a neutral relay at each station having an energizing circuit closed when its corresponding polar line relay assumes either of its polar positions, station selecting means at each station selectively controlled in accordance with the polar position of its corresponding polar line relay during the time that said corresponding polar line relay assumes a polar position and said corresponding neutral relay has not yet responded, whereby said stations are selected in accordance with the polarity of impulses applied to said line circuit, and selector means responsive to the operation of the line relay only at a selected station. 15 20 25

19. In combination, a line circuit interconnecting a plurality of stations, a polar line relay included in said line circuit at each of said stations, means for impressing a plurality of impulses of selected polarities on said line circuit, means responsive to said impulses for operating said line relays, a neutral relay at each station having an energizing circuit closed when its corresponding polar line relay assumes either of its polar positions, other relay means at each station having an energizing circuit including a back contact of its corresponding neutral relay and a polar contact of its corresponding polar relay in one or the other of its polar positions as previously determined, whereby said stations are selectively divided into groups in accordance with the polarity of an impulse applied to said line circuit, and selector means responsive to the operation of the line relay only at a selected station. 30 35 40

20. In combination, a line circuit, means for selectively applying positive or negative energy to said line circuit, a pair of polar line relays each having contacts capable of assuming either of two positions in accordance with the polarity of the energy applied to said line circuit, a pair of neutral relays energizing circuits closed for each of said neutral relays when the contacts of said polar relays assume either of their positions, relay means selectively controlled in accordance with the positions assumed by the contacts of said polar relays during the pick-up period of said neutral relays and selector means selectively controlled by said relay means to be responsive to the further operation of said line relays after said neutral relays are picked up. 45 50 55 60

21. In combination, a line circuit, means for selectively applying positive or negative potential to said line circuit, a plurality of polar line relays included in said line circuit each of said polar relays having contacts operable to either of two polar positions, a neutral relay for each of said line relays, an energizing circuit for each of said neutral relays closed whenever the contacts of its respective polar relay assume polar positions, and selector means for each of said polar line relays, certain of said selector means responding to their polar relays only when their contacts assume one polar position during the pick-up period of their neutral relays and certain other of said selector means responding to their polar re- 65 70 75

lays only when their contacts assume the other polar position during the pick-up periods of their neutral relays, whereby said selector means may be selectively controlled in accordance with the 5 polarity of the potential placed on said line circuit.

22. In a remote control system, a line circuit, means for energizing said line circuit with a plurality of different series of impulses having distinctive characters, a plurality of line relays for repeating the impulses of each series, a plurality of selector means, one for each of said line relays, means causing certain of said selector means to be responsive to its respective line relay during 10 a particular one of said series of impulses only if the first impulse of that series is of a particular distinctive character, means causing certain other of said selector means to be responsive to its respective line relay during a particular one of 15 said series of impulses only if the first impulse of that series is of another particular distinctive character, and means for preventing any response of said selector means to a series of impulses when the first impulse of the series is not 20 of said particular character.

23. In a remote control system, a line circuit, code transmitting means for energizing said line circuit with any one of a plurality of different series of code combinations of impulses of selected 30 characters, a plurality of step-by-step means each operated through a cycle of operation in response to a series of impulses only when the first element of the series is of a particular character, electro-responsive means responsive to succeeding 35 code elements of said series only when said step-by-step means operates through a cycle of operation, and means preventing any operation of said step-by-step means by succeeding impulses of a series when the first element of said 40 series is not of said particular character.

24. In a communication system for centralized traffic control, a control office, switch control devices and signal control devices located at a plurality of field stations, a line circuit for connecting the control office to the several field stations, a series of stepping relays at each field station, a line relay in said line circuit for energizing said stepping relays sequentially, a station conditioning relay at each field station responsive to the polarity of energization of said line circuit for determining whether or not said bank of stepping 45 relays shall be operated by subsequent operations of said line relay, a manually operable means for each station, means controlled by said manually operable means for determining the polarity of energization of said line circuit at a predetermined time to cause energization of said station conditioning relay and operation of the bank of stepping relays at that particular station, and 50 control circuits for said switch and signal control devices governed by said stepping relays.

25. In a communication system for centralized traffic control, a stepping line circuit extending from a control office to a field station, a line relay in said line circuit at the field station, a plurality of stepping relays at the field station, circuits controlled by said line relay for energizing said stepping relays sequentially one at a time, means at the station responsive to the polarity of energization of said line circuit at a particular 55 time for determining whether or not said stepping relays shall be operated by subsequent impulses on said stepping circuit, and manually controllable means in said control office for determining the polarity of said energization of the line circuit.

cuit to cause operation of said stepping relays depending upon the condition of said manually controllable means.

26. In a communication system for centralized traffic control, a stepping line circuit extending from a control office to a field station, a line relay in said line circuit at the field station, a plurality of stepping relays at the field station, circuits controlled by said line relay for energizing said stepping relays sequentially one at a time, 5 means at the station responsive to the polarity of energization of said line circuit at a particular time for determining whether or not said stepping relays shall be operated by subsequent impulses on said stepping circuit, manually controllable means in said control office for determining the polarity of said energization of the line circuit to cause operation of said stepping relays depending upon the condition of said manually controllable means, and control relays at the field 10 station for governing the operation of traffic controlling devices and having circuits selectively controlled by said stepping relays.

27. In a remote control system of the synchronous selector type; a stepping circuit; means applying a series of impulses to said stepping circuit; means selectively determining the character of each impulse of said series of impulses; a line relay in said stepping circuit distinctively responsive to each impulse of said series of impulses 15 in accordance with the character thereof; a slow-acting relay controlled by a distinctive operation of said line relay, said slow-acting relay being picked up at the beginning of said series of said impulse and dropped at the end of said series of impulses; and a stepping relay bank initially controlled by the response of said line relay to an impulse of a distinctive character and said slow-acting relay in its de-energized position, said stepping relay bank being selectively responsive 20 to the distinctive operation of said line relay by a particular impulse of said series whereby said bank thereafter responds or fails to respond to all other operations of said line relay by said series of impulses.

28. In a remote control system of the synchronous selector type; a stepping circuit; means applying a series of impulses to said stepping circuit; means selectively determining the character of the first impulse of said series of impulses; a line relay in said stepping circuit distinctively responsive to each impulse of said series of impulses in accordance with the character thereof; a slow-acting relay controlled by said line relay, said slow-acting relay being picked up at the beginning of said series of impulses and dropped 30 out at the end of said series of impulses; and a stepping relay bank initially controlled by the response of said line relay to the first impulse of a distinctive character and said slow-acting relay 35 in its de-energized position, said stepping relay bank being selectively responsive to the distinctive operation of said line relay by the first impulse of said series whereby said bank thereafter responds or fails to respond to all other operations of said line relay by said series of impulses.

29. In combination with a control relay, a selector of the relay type adapted to be operated by said control relay and comprising a series of counting relays interconnected to permit successive energization of the relays; a pick-up circuit for each said counting relay including a contact of the control relay, a front contact of the next preceding counting relay and a back contact of the second preceding counting relay; and means 40

effective when each counting relay becomes energized and including a back contact of such energized relay for releasing the next preceding relay.

30. In combination with a control relay, a selector of the relay type adapted to be operated by said control relay and comprising a plurality of counting relays arranged in order; a pick-up circuit for each odd-numbered counting relay including a front contact of the next preceding counting relay, a back contact of the second preceding counting relay and a contact of said control relay closed in one position; a pick-up circuit for each even-numbered counting relay including a front contact of the next preceding counting relay, a back contact of the second preceding counting relay and a contact of said control relay closed in another position; and a stick circuit for each counting relay including a back contact of the next succeeding counting relay.

31. A selector of the counting relay type comprising a series of counting relays interconnected to permit successive energization of the relays, a pick-up circuit for each said relay including a front contact of the next preceding counting relay and a back contact of the second preceding counting relay, and a holding circuit for each said counting relay including its own front contact and a back contact of the next succeeding counting relay, a control relay governed from a distant point and provided with contacts which are alternately closed, one contact of said control relay being included in the pick-up circuit for each odd-numbered counting relay, and another contact of said control relay being included in the pick-up circuit for each even-numbered counting relay. 5
